UNITED STATES PATENT OFFICE

JOSEPH GABOR, OF NEW YORK, N. Y.

ATTACHABLE RADIATING ELEMENT

Application filed March 10, 1930. Serial No. 434,668.

This invention relates to radiators or pipe coils by which heat, carried through the agency of steam in conduction pipes from a generating source, is issued directly from surfaces carried by or attached to the pipes, and the main object of the invention is the provision of a device of the class herein described in which, preferably by attaching metal fins to the steam-pipes, the heat radiating surfaces are increased.

As spaced hollow metal castings or coils have been used in radiator construction, in connection with steam pipes, there being pipe sections between the castings, another object of the invention is to utilize the interposed sections for carrying the metal fins with a view to increasing the heat emitting properties of the radiator.

A further object is to provide an improved construction in which the elements of the radiator are so co-ordinated, structurally and functionally, as to insure sufficient heat radiation without making extensive alterations in existing heating systems.

Furthermore, as radiators have been installed in fixed positions on pipes, and as it has frequently happened that heat distribution has been required, at least for temporary periods, at intervening points, that is to say between the fixed radiators, still another object in the invention is the provision of removable radiator, whereby the particular localities to be heated, adjacent a steam pipe, may be varied according to requirements, without the use of tools.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawings, which latter show embodiments of the invention as at present preferred.

In said drawings:

Fig. 1 is an elevational view, partly sectional, of an improved radiator.

Fig. 2 is a vertical sectional view on the line 2—2 of Fig. 1.

Fig. 3 is a perspective of my novel attachment per se.

Fig. 4 is a top plan view of the radiator 55 shown in Fig. 1.

Fig. 5 is an elevational view of a modified form of radiator.

Fig. 6 is a vertical sectional view on the line 6—6 of Fig. 5.

Referring particularly to the drawings by reference characters, the numerals 10 and 11 represent steam pipes, with which heat radiating units 12, of cast iron or the like, are incorporated, there being threaded apertures in the ends 13 of these units to receive the externally threaded terminals 14 of the said pipes, while interposed pipe sections or nipples 15 are similarly externally threaded for insertion in opposite apertures of the said ends 13, 70 so that the inner passages of the pipes communicate with the hollow interiors of the units 12.

In order to increase the quantity of heat radiated by the pipes at any selected point, 75 I provide U-shaped attachments 16, each of which is struck out from or otherwise formed of suitable metal, such as brass, copper, aluminum, iron or other ferrous metal. While each attachment 16 is itself U-shaped its respective leg and bight portions are also U-shaped in cross section.

Each leg of the radiator 16 includes a pair of like flanges or fins 17, between the inner edges of which are body portions 18; and 80 while the latter portions are connected by a portion 19, the flanges 17 have disposed therebetween flanges 20. As the pipes, such as 10 and 11, may be spaced any required distance apart, the legs of the radiator may also be of any suitable length, it being preferable to allow the terminals of the legs to depend slightly below the plane of the lowermost surface of the bottom pipe. While the body portion 19 may be of any required dimension to suit 85 specific pipe diameters, the body portions 18 preferably rest loosely against the opposite sides of the pipes, to allow of easy installment or removal of the device.

As illustrated in Figs. 1 to 4, the legs of 100

the members 16 are of about the same length as the castings 12; and while the said members occupy the space between the castings the inner wall portions 18 and 19 absorb heat from the pipes 10 and 11 and radiate the heat through the parallel flanges of the said members, the result being a material increase in the efficiency of the radiator.

In Figs. 5 and 6 I have shown a pipe 10', which is U-shaped in configuration, and on the legs of which a number of heat radiating members 16, are shown, in spaced relation; but since these members are easily removable, other arrangements of the members may be made, or other parts of the pipe may be utilized for carrying the said members, which may, for instance, be placed closer together when increased heat radiation is required.

The hereinbefore described construction admits of considerable modification without departing from the invention; therefore, I do not wish to be limited to the precise arrangements shown and described, which are as aforesaid, by way of illustration merely. In other words, the scope of protection contemplated is to be taken solely from the appended claims, interpreted as broadly as is consistent with the prior art.

What is claimed as new is:

30 A removable heat radiating attachment for a radiator having spaced steam pipes, comprising U-shaped heat radiating members, the respective legs of said members including parallel spaced flanges, the bight portions 35 of said members including also parallel spaced flanges, which latter are integral with said first flanges, the respective legs of said members embracing opposite sides of the spaced steam pipe portions, and the bight 40 portions of said members adapted to rest on one of the steam pipe portions.

In testimony whereof I hereby affix my signature.

JOSEPH GABOR.
